Lars Peder Christensen,

UNITED STATES PATENT OFFICE.

LARS PEDER CHRISTENSEN. OF CHICAGO, ILLINOIS.

BUTTON.

1,202,031.

Specification of Letters Patent.

Patented Oct. 24, 1916.

Application filed November 16, 1912. Serial No. 731,824.

To all whom it may concern:

Be it known that I, LARS PEDER CHRISTENSEN, a citizen of the United States, residing at Chicago, in the county of Cook and State 5 of Illinois, have invented new and useful Improvements in Buttons, of which the following is a specification.

My invention relates to buttons.

One object of my invention is to provide 10 an improved form of button which may be securely fastened to clothing or the equivalent which does not necessitate the sewing of the button to the clothing.

Another or more specific object of the invention is to provide a button head device 15 which is attachable to clothing by means of a suitable staple device.

Still another object of the invention is to provide means on the button head device 20 which will deflect or bend the prongs of the staple, as the same is driven into the button head device.

Another object of the invention is to provide a button of this kind that is of such 25 construction that an ornamented head or covering of any preferred design may be effectively fastened or secured thereto.

Still further objects of the invention are to provide a device that is of simple construction, that employs few parts, and which 30 may be manufactured at a minimum cost.

The preferred embodiment of the invention is described hereinafter, in connection 35 with drawings accompanying this application.

In said drawings:—Figure 1 is a vertical sectional view through a button constructed 40 in accordance with my invention, the same being suitably fastened to cloth, and on an enlarged scale. Fig. 2 is a top view of the cloth engaging section of the button; Fig. 3 is a top view of the other section of the button; Fig. 4 is a top view of one form of staple; Fig. 5 is an elevation of such form 45 of staple; Fig. 6 is a top view of another form of staple, and Fig. 7 is an elevation of the latter form of staple.

In the drawings, like reference characters 50 designate like or similar parts throughout the several views.

The button comprises a head device having complementary sections 1 and 2, the latter being referred to hereinafter as the cloth engaging section, for convenience. Said sections 55 are manufactured separately and are fastened together at their edges as by clench-

ing a flange 3 on the section 1, over the edge of the section 2.

The cloth engaging section 2 is provided with a suitable rib or annular wall 4 which defines a boss 5 interior thereof, which boss it will be seen by reference to Fig. 1, projects below the remainder of the section 2 to effectively provide a space for the reception of that portion of the cloth adjacent the buttonhole through which the button head is passed. Said boss is preferably struck inwardly at 6 to provide a transverse groove 7.

The section 1 is provided with a rib 9 so constructed as to be distanced slightly from 70 the rib 4 and to form a cap thereover. It will be seen that the ribs have arcuate walls and provide intermediate the same arcuate or tortuous channels.

The button head device is attached to cloth 75 or other material which may be designated 10, by driving a staple member through the cloth and into the button. Such a staple member may be of any suitable form, one form being shown in Figs. 4 and 5. In said 80 figures four pointed prongs are provided and designated 11, and are joined together by a plate designated 12. Another form of staple is shown in Fig. 6 and therein it is shown substantially U-shaped and as having 85 two pointed prongs 13. When the button is attached to the cloth and enters the opening 8 extending into the interior of the button head, such prongs enter the space intermediate the rib 4 and cap rib 5. It is necessary 90 that the staple be driven by a suitable instrument such as a hammer, and when so driven, the prongs by the engagement with the walls of the ribs 4 and 9 will be bent or deflected as shown in Fig. 1, to extend over 95 the rib 4; thereby effectively attaching the button head to the cloth, such as 10.

The button head may be rendered ornamental in any desired manner, as by embossing the section 1 to provide a desired 100 design. If preferred, a metal cover such as 14 may be clenched or fastened at the flange 3, as shown in Fig. 1, and further if desired, this metal cover may have secured or fastened around the same, a leather or other 105 flexible covering such as 15.

The ribs 4 and 9 are shown as annular in form, but it is obvious that the same need not be annular, but may be of any width or extent desired. Also it is to be understood 110 that changes in the details of construction of the device, within the spirit and scope of

the appended claim may be made, as only the preferred embodiment of the invention has been illustrated and described.

Having thus described my said invention, 5 what I claim as new and desire to secure by Letters Patent is:—

A button comprising an inner section crimped adjacent the central portion to provide an inwardly extending rib surrounding 10 the central portion of the inner section, the inner portion being provided with openings, and crimped to provide a reinforcing rib extending between the openings, a plate having its edge portion secured to the edge 15 portion of said inner section and having its

central portion crimped to extend about the rib and into the space inclosed thereby in close proximity to said rib, and an attaching member provided with prongs extending through the openings of the central portion of said inner section upon opposite sides of the reinforcing rib and passing through the space between said rib and the crimped portion of said plate in tight engagement with the rib. 20

LARS PEDER CHRISTENSEN.
